CLAIM

The ornamental design for a fishing lure holder, as shown and described above.

DESCRIPTION

FIG. 1 is a front perspective view of a fishing lure holder, showing our new design;

FIG. 2 is a front elevation view thereof;

FIG. 3 is a rear elevation view thereof;

FIG. 4 is a right-side view thereof;

FIG. 5 is a left side view thereof;

FIG. 6 is top view thereof;

FIG. 7 is a bottom view thereof;

FIG. 8 is a rear perspective view thereof;

FIG. 9 is a top perspective view thereof; and,

FIG. 10 is an environmental top perspective view thereof. The broken lines of the drawing show portions of the fishing lure holder and environmental structure that form no part of the claimed design.

1 Claim, 10 Drawing Sheets
